PROCESS AND APPARATUS FOR MAKING
SAUSAGE CASINGS AND THE LIKE

Ralph L. Atkinson, Boston, Mass.

Application May 1, 1933, Serial No. 668,712
Renewed August 4, 1934

4 Claims. (Cl. 18—15)

My invention relates to improvements in the art of making tubing of cellulose hydrate for sausage casings and the like. Heretofore such tubing has been formed of cellulose hydrate, by 5 dissolving cellulose by the well known viscose process, to form a viscous solution, and extruding the solution continuously through an annular die, thus forming it into a thin-walled tubing and thereafter coagulating or precipitating the cellulose hydrate of the tubing by applying thereto a suitable coagulant or hardening agent. A process and apparatus for this purpose are disclosed in United States Patent No. 1,163,740, granted to Cohoe December 14, 1915. My invention provides certain improvements in process and apparatus of this character, whereby a more uniform and satisfactory product may be continuously, uninterruptedly and rapidly produced with a minimum of attention and manipulation upon 10 the part of the operator.

The preparation of the viscose solution, as it is used in my process and apparatus, is well known and need not be here described, save that it is desirable to use a solution of relatively high viscosity of the nature of a plastic as thereby the tubing as it is produced is of greater strength and tenacity during the period before it has been completely coagulated and hardened. I may employ any of the well known coagulants, commonly 15 employed for precipitating viscose from solution, but preferably employ an acid reagent for this purpose, dissolved in water in the usual concentration.

My invention relates to the process and apparatus for extruding and coagulating the tubing.

In the drawings accompanying and forming a part of this specification, Figure 1 shows my improved apparatus in vertical longitudinal section, parts being shown in elevation, and

Fig. 2 is a vertical section, partly in elevation, of the tube-forming head or extruding device.

The apparatus shown in Fig. 1 comprises a precipitating tank 3, a washing or finishing tank 4, a supply tank 5 for the coagulant or precipitating agent and an overflow tank 6. The forming head 7 is suitably supported in tank 3 with its annular die or forming opening directed downwardly, and suitable guides, to be presently described, are located within and above the tank 10 for the purpose of receiving the tubing 9 as it is formed and guiding it through the coagulant bath within the tank by which the tube is hardened and set.

Referring now more particularly to Fig. 2, it 15 will be seen that the forming head comprises a

main body or casing 10, shown as an annular casting or sleeve, having a cover 11 bolted to the upper end thereof and a conical annular die member 12 bolted to the bottom thereof. Save for the annular die opening 23 through which the cellulose solution is extruded, the lower end of the body and the chamber thereof are closed by an internal die member or mandrel 13. The body of the mandrel 13 is tapered on its outer periphery to substantially correspond to the taper 10 of the inside of the wall of the die 12 and is spaced from the latter, with which it is coaxial, a suitable distance to provide an annular passage between the two of the proper size to form a 15 tubular film of the thickness required to produce a tubing of the desired wall thickness. In the specific structure shown, the mandrel 13 is formed with a conical upper end and is supported from the cover 10 by a sleeve 14 threaded into the mandrel at 15 and into an opening in 20 the cover at 16. The sleeve is formed with an annular flange 17 the upper surface of which is shaped to conform to the bell shape of the upper surface of the mandrel. Obviously, by turning the sleeve 14 it may be adjusted vertically 25 through the cover 11 to adjust the thickness of film produced between the die 12 and the mandrel. The mandrel may be accurately centered in the die by means of the adjusting screws 18 threaded through the walls of the casting 10 and 30 engaging the sleeve 14.

The viscose solution is supplied to the chamber 19 of the forming head through a pipe 20 connected with a suitable supply vessel to be referred to later, containing a body of the solution.

A bell-shaped skirt or extension 21 is formed on or secured to the mandrel 13, the lower portion of the skirt being rounded as at 22 and of somewhat larger diameter than the die opening 23.

A T coupling 24 is screwed to the upper end 40 of the sleeve 14, the opposite branch of the T being closed by a plug 25. The third opening of the T receives a pipe 26 through which a supply of coagulant or precipitating agent is received as will be presently described. An exhaust pipe 45 27 extends through the plug 25 to a suitable distance below the skirt 21 of the mandrel and also passes through a horizontal diaphragm 28 which cuts off communication between the upper and lower portions of the bell-shaped skirt. The skirt 50 is provided above and below the diaphragm with annular series of openings 29, 30 for a purpose which will now be described.

When the apparatus is in operation, the forming head receives a constant supply of cellulose 55

solution which is pumped through the pipe 20 from a suitable source, the solution filling the chamber and being forced or extruded through the annular opening between the die and mandrel, and as the formed tube emerges it travels over the convex surface of the lower end of the bell and is somewhat stretched thereby. The forming head of the lower end thereof dips into the bath of coagulant or precipitating agent within the tank 3 and therefore as the tube emerges it is at once subject to the hardening effect of the coagulant by which it is surrounded. At the same time, coagulant is constantly supplied through the pipe 26 and the sleeve 14 to the interior of the mandrel and the upper portion of the bell-shaped skirt 21. The upper end of the skirt is reduced exteriorly at 31 so that an annular chamber is formed between the same and the surrounding tubing 32 and the openings 29 above mentioned are so located as to communicate with the upper end of this chamber adjacent the die or extrusion opening. A lower annular series of openings 30 likewise communicate with this chamber, at its lower end, and the coagulant supplied to the interior of the mandrel and bell flows through the upper openings, washes and hardens the inner surface of the tubing and flows from the lower end of the chamber into the interior of the lower portion of the skirt or bell. The coagulant is thus supplied also to the interior of the formed tubing between the bell and the first guide 8 under sufficient head to maintain the tubing distended against the pressure of the body of coagulant in tank 3. Further, enough of the coagulant escapes past the guide 8 to distend the tubing beyond said guide, as will be explained later. From the interior of the tubing an amount of coagulant escapes through the outlet pipe 27 to balance the inflow after normal conditions have been established.

As the tubing is quite tender when freshly formed and therefore readily stretched or deformed until the cellulose is coagulated or hardened, it is important that the interior pressure of the coagulant be nicely adjusted to substantially equal, or, preferably, slightly overbalance the external pressure of the body of coagulant in tank 3 in which the tubing is submerged, so that the tubing may be properly distended but not unduly or irregularly stretched. For this purpose the level of the coagulant in supply tank 5 from which the coagulant flows through the tube 26 to the interior of the tubing is carefully adjusted to and maintained at a height slightly above the height or level of the liquid in tank 3. A suitable means for this purpose is shown in the pivoted adjustable overflow pipe 34 in the supply tank which communicates with pipe 35 discharging into the overflow tank. The level of the coagulant in tank 3 is maintained constant by an overflow pipe 36 likewise discharging into the overflow tank 6. From the latter, the coagulant is returned in sufficient volume to maintain the level in the supply tank by a return pipe 37 and pump 38.

As heretofore stated, the tubing as it is formed passes through the coagulant in tank 3 and is carried first around the guide 8, which may be an idle roll, and then upwardly through the bath to a pair of rolls 39 between which it passes, the rolls being so adjusted relative to each other as to properly flatten the tubing between them without exerting undue pressure thereon. The tubing passes around roll 8 sufficiently freely to permit an amount of coagulant to pass through

the tubing about the roll and into the upwardly moving tubing between the guide roll 8 and the rolls 39 to hold the same partially distended against the pressure of the body of coagulant in the tank, tending to collapse it. 5

From the flattening rolls 39, the tubing passes back and forth around guide rods 40, 41 located above the level of the coagulant and guide rods 42 suitably located within the tank 3 and toward the bottom thereof until the material of the tubing is completely or sufficiently coagulated. From the last guide rod 42, the tubing passes over guide rods 43, 44 into the washing or other treating tank 4 where it is caused to travel similarly up and down through the tank about guide rods 15 45, 46.

In the practice of my process of making cellulose hydrate tubing, I prefer to use a viscose solution of relatively high viscosity and have successfully employed solutions of viscosities 20 ranging from 250 to 450 seconds according to the official method of the American Society for Testing Material as given in A. S. T. M. Tentative Standards, 1931, p. 358, "Consistency", the material being tested at 18° C. I have found that 25 most satisfactory results are obtained toward the upper limit of this range of viscosity. Preferably the pressure of the internal body of coagulant below the forming head is so regulated as to 30 distend or stretch the tubing laterally so that 35 it exerts little, if any, pressure upon the bell 22 and it may even to advantage be stretched by the inner coagulant pressure to a diameter slightly in excess of that of the bell. The pressure of the internal body of coagulant below the bell is such 40 as to prevent any substantial contraction of the tubing as it travels from the bell to the reversing roller 8. Indeed, I have found that the bell may be omitted altogether and by properly regulating the pressure of the internal body of coagulant 45 the desired lateral or circumferential stretching may be satisfactorily accomplished.

It is to be understood that a drawing or tension mechanism, which may be of usual or known character, such as constantly driven rolls or a 45 reel, is employed to take up or draw the tubing from the forming head and through the several baths to which it is subjected, the tubing being taken up at a rate at which it is substantially stretched or drawn. I have successfully employed 50 a take-up rate three or four times as great as the rate at which the tubing is formed by the forming head. The distension of the tubing by the internal pressure, together with the longitudinal tension to which it is subjected, serves to 55 flatten the tube so that it passes smoothly and without wrinkles around the roll 8, and at the same time the tension is not sufficient to prevent an amount of internal coagulant to pass the roller and distend the upwardly moving length 60 of tubing between said roller and a pair of rolls 39.

From the rolls 39 the tubing passes back and forth through the coagulating bath as heretofore described and then through a further bath or baths for further treatment. This further treatment may include such well-known steps as subjecting the material to an additional bath of relatively weak acid coagulant, washing and impregnation with glycerine. After the treatment is completed the tubing may be wound up or 70 subjected to a suitable drying operation immediately.

I claim:

1. In a forming head of the class described, a main body for receiving the material from which 75

tubing is to be formed by extrusion, said body having an exterior die member, a mandrel concentric and cooperating with the die member to form an annular die opening therewith, a skirt on said mandrel having a lower portion of enlarged diameter as compared to the die opening, a sleeve supporting said mandrel and communicating with the interior thereof, means for supplying the sleeve with coagulant, the skirt of the mandrel being formed with upper and lower passages permitting the circulation of coagulant from the interior of the skirt through the latter and into a chamber formed between the skirt and the newly formed tubing, said skirt also being formed with lower openings permitting the coagulant to escape from said chamber to the interior of the skirt.

2. A process of forming tubing of cellulosic material for sausage casings or the like having a predetermined diameter comprising extruding downwardly in tubular form a plastic solution of cellulose and directly submerging the same in a coagulant bath, leading the tubing first downwardly and then upwardly in the bath, continuously supplying coagulant to the interior of the downwardly and upwardly moving and submerged tube portions, determining the diameter of the tubing by establishing the pressure of the coagulant within the tubing in excess of that exerted by the bath, maintaining a sufficient volume of coagulant within the tubing to hold the predetermined diameter, evacuating the excess coagulant from the interior of the tubing, collapsing the upper end of the upward tube portion within the bath, continuously removing the tubing from the bath and thereafter feeding the collapsed tubing through a second coagulant bath.

3. A process of forming tubing of cellulosic material for sausage casings or the like having

a predetermined diameter comprising extruding downwardly in tubular form a plastic solution of cellulose and directly submerging the same in a coagulant bath, leading the tubing first downwardly and then upwardly in the bath, continuously supplying coagulant to the interior of the downwardly and upwardly moving and submerged tube portions, determining the diameter of the tubing by establishing the pressure of the coagulant within the tubing in excess of that exerted by the bath, maintaining a sufficient volume of coagulant within the tubing to hold the predetermined diameter, evacuating the excess coagulant from the interior of the tubing, collapsing the upper end of the upward tube portion within the bath, continuously removing the tubing from the bath and thereafter feeding the collapsed tubing through a second coagulant bath.

4. Apparatus for forming tubing of cellulosic material for sausage casings or the like having a predetermined diameter comprising a forming head having a tubular die, a bath of coagulant into which the die opens downwardly, the delivery end of the die being submerged in the bath, a lower guide member within the bath and below the forming head about which the tubing is led, an upper guiding member to and about which the tubing is led from the lower guide member, and means for supplying coagulant to the interior of the tubing portions between the lower guide member and the forming head and upper guiding member, respectively, at a pressure in excess of that exerted by the bath and in sufficient volume to hold the predetermined diameter.

RALPH L. ATKINSON. 35
